PENCIL

Friedrich Wilhelm Haack, Berlin, Germany

Application July 25, 1934, Serial No. 736,944

1 Claim. (Cl. 120—19)

This invention relates to pencils and particularly to the type of pencils having a lead of a relatively great length which can be shifted and fixed from the outer side of a case by means of a 5 slideable sleeve.

One object of the invention, among others, is to provide pencils of this type behind the shiftable lead with a second pin also movably situated in the pencil case and adapted to be pushed out 10 of the open top end of the pencil case, the second pin consisting of a soft or hard rubber, a pastel, a lip stick or the like.

Another object of the invention is to provide a cheap, reliable and well protected means for 15 holding the second pin and operating it.

A still further object of the invention is to provide means for shifting and fixing the second pin in any desired position of the case.

Another object of the invention is to construct 20 the pencil in such a way that the second pin being moved and secured by the sleeve operating the lead holder.

One form of a pencil embodying my invention, and in the construction and use of which the objects herein set out, as well as others, may be 25 attained, is illustrated in the accompanying drawing, in which:—

Fig. 1 is a view of a pencil constructed in accordance with this invention.

Fig. 2 is a section on line 2—2 of Fig. 1, the 30 slideable sleeve being shown in an enlarged scale.

Fig. 3 is a longitudinal section substantially on line 3—3 in Fig. 2, showing the slideable sleeve, the lead, the lead holder and the means carrying the second pin, but not illustrating the pencil 35 case.

Fig. 4 and Fig. 5 show details of the holder of the second pin.

Fig. 6 is a view of the pencil shown in Fig. 1, 40 but in changed position of the slideable sleeve.

Fig. 7 is a section, enlarged scale, on line 7—7 of Fig. 6.

The various novel features of the invention will be apparent from the following description and 45 will be particularly pointed out in the appended claim.

In the embodiment illustrated in the drawing, the pencil comprises a case 1 with a longitudinal slot 2 and a ring 3 slideable on the case 1. In the 50 ring 3 an eccentric groove 24 is provided. Between the pencil case 1 and the ring 3 a double sided beaded band 7, 12 with flaps 6 is situated in the slot 2. The edges of the flaps 6 are folded outwards so that they form clamping cheeks 55 provided with projections 11 which hold the flaps

clear of the inner wall of the ring when the ring is in certain positions and these projections increase the resilient action of the flaps (Fig. 2). The clamping cheeks engage in the eccentric groove 24 of the ring 3. In the rounded portion 5 of the beaded band 7, 12 is fitted the holder 8 for the lead 4. The holder 8 consists preferably of a helical band. A short sleeve 9 engages the helical lead holder 8 and has at the front end an inwardly directed tooth 10 engaging the coils 10 of the helical band 8. The sleeve 9 being shiftable along the helical band 8 its tooth 10 acts to drive the lead end portion out from the holder 8 and also forms a stop for engaging a new lead 4 in the holder 8.

The slideable ring 3 has a mark to show the position in which the ring 3 can be moved together with the lead holder 8 and the beaded band 7, 12 along the pencil case 1. The mark consists of a longitudinal groove 5, but may also be constructed in any suitable other way. By turning the adjusting ring 3 to the right or the left, one of the clamping cheeks 11 is pressed against the pencil case 1 so that the adjusting ring 3 and thereby the lead holder 8 with the lead 4 are 15 clamped.

For improving the availability of the pencil, behind the lead 4 a second pin 18 is provided which is movably situated in the pencil case 1. The second pin 18 is shiftable and fixable by 30 means of the adjusting ring 3 operating the lead holder and may consist of a soft or hard rubber, a pastel, a lip stick or the like. For using the pin 18, it is moved by means of the adjusting ring 3 and in the position of the mark 5 of the ring 3 as shown in Fig. 1, from the writing position or the position of retirement of the lead 4, into the position of Fig. 6 in which the pin 18 projects from the top of the cap 19 covering the pencil case 1 and having a suitable guiding bore 40 23. Then the pin 18 is fixed in the same manner as in the case of fixing the lead 4 by lateral turning the adjusting ring 3 to the right or the left whereby the adjusting ring and the lead holder 8 are clamped. After use of the pin 18 it is withdrawn into the interior of the pencil case 1 by 45 re-turning and moving the ring 3 in any desired position.

Preferably the pin 18 consists of a rubber. The operation of the rubber 18 by means of the 50 adjusting ring 3 offers the advantage that a long rubber may be provided, the length of which may be still greater than it is shown in Figs. 1, 2 and 3. Another advantage is the easy and quick operation, the rubber 18 being moved and 55

fixed in the same way as the lead holder and the lead only by shifting and turning the adjusting ring 3.

The connection of the pin 18 with the ring 3 respectively with the lead holder 8 and the beaded band 7, 12 may be constructed in the following way: In the helical band 8 which is fitted in the rounded portion 7 of the beaded band 12, a pin 13 having a threaded upper end 13' is fastened. This pin bears a socket 14 which, in the construction of Fig. 3 and Fig. 4, is screwed upon the pin 13 by means of a threaded bore 15, but of course may also be formed in any suitable other way and, e. g. corresponding to Fig. 5 may be provided with a pressed threaded portion 16 or the like. The socket 14 constitutes the holder of the rubber 18, pastel or lip stick which is either only put into the socket 14 or also secured in it by additional means e. g. by inwardly directed portions 17 of the socket 14. The socket 14 may be in constant connection with the pin 13, 13' and therefore rigidly joined or made of one piece with the pin. The pin 13, 13' limits the depth of the rubber 18 and acts as a stop for the lead 4 or the small sleeve 9 the tooth 10 of which engaging the coils of the helical band 8, so that the helical band 8 may be of a cylindrical form.

In order to prevent restricting of the slot 2 of the pencil case 1 when the cap 19 is fixed on the top end of the pencil case 1, whereby the displacement of the adjusting ring 3 and therefore also of the lead holder 8 and the two pins 4 and 18 would be hindered or prevented in the zone of the upper part of the slot 2, the ring 20 of a clip 21 mounted on the pencil case 1 is

provided with a projection 22 engaging the slot 2. The projection 22 is situated diametrically opposite to the clip 21. By this projection 22 of the clip ring 20 not only restricting of the slot 2 near the top end of the pencil case 1 is prevented, but also attained that the clip 21 stands always diametrically opposite to the slot 2 of the case 1 and is secured against turning so that the cap 19 does not become loose. The slotted upper end of the casing 1 is reduced to provide a shoulder against which the ring 20 is maintained by the cap 19. The cap 19 is secured on the reduced end in any suitable manner (not shown).

Changes in the details of the various elements and in their arrangement may be made without departing from the spirit of the invention as defined in the appended claim.

I claim:

In a mechanical pencil, a tubular casing, a lead holder movable for alternate projection and retraction of the lead carried thereby, said casing being formed to provide an open ended slot extending longitudinally thereof, operating means on the exterior of the casing having a member projecting through said slot and engaging said lead holder to move the same as the operating means is moved, the slotted end of said casing being reduced to form a shoulder, a ring seated on said reduced end, an inwardly extending portion on said ring, said portion fitting in said slot to prevent accidental compression of the same, and a cap fitted on said reduced end and maintaining said ring against said shoulder.
